COLLAPSIBLE DISPLAY CONTAINER FORM-
ING RIM AND TRIM FOR STANDS

Hamlet Lee Moremen, Seattle, Wash., assignor to Washington State Apple Advertising Commission, Wenatchee, Wash., a corporate body of Washington

Application October 4, 1949, Serial No. 119,509

3 Claims. (Cl. 211—133)

1

This invention relates to article display devices and more particularly to a collapsible display container which is adapted to form a rim and trim for such display devices.

In the display or exhibition of articles, such as oranges, apples, summer squash, head lettuce and the like, the articles are frequently piled up on stands but, unless some means is provided to confine the articles making up the base portions of the pile, these articles are apt to roll or move outwardly, thus disarranging the pile.

An important object of this invention is to provide a novel collapsible display container forming a rim and trim for an article-displaying stand or support.

Another important object is to provide such a container which is ideal for association with one or more upended packing boxes, such as orange or apple crates, to provide a support, so as to form a rim extending upwardly from the upwardly-facing end wall of the box or crate, or grouped crates. Such an arrangement permits the use of the containers in which the articles to be displayed were packed.

Still another important object is to provide such a collapsible display container to form a rim and trim for an associated upwardly-extending support, which rim will not tend to bulge outwardly beyond the vertical planes of the support.

A further important object is to provide a rim and trim which will not tend to make a display stand topheavy when articles are piled thereon and within the confines of the rim.

Instead of providing a solid, imperforate bottom wall for my display container, only a relatively narrow flange is provided instead. This economizes material and, when this flange overlaps the outermost portions only of the upwardly-facing walls of a group of upended slatted crates, properly arranged, the assembly of parts permits air circulation through the openings formed in the grouped upwardly-facing walls, when the several slatted crates are upended and grouped. This tends to ventilate the piled-up display.

Of course, it is often desirable to provide a collapsible display container, and it has been my aim to provide a container which may be collapsed to provide but four thicknesses of material, which material may be corrugated board.

Other objects and advantages of this invention will be apparent during the course of the following detailed description of the invention, taken in connection with the accompanying drawing forming a portion of this disclosure, and in which drawing:

Fig. 1 is a perspective view of the assembled novel display container.

2

Fig. 2 is a top plan of the collapsed novel display container.

Fig. 3 is a side elevation of the collapsed container of Fig. 2.

Fig. 4 is an enlarged vertical section of the same substantially on the line 4—4 of Fig. 3.

Fig. 5 is a perspective view of the display container secured to a suitable support, as four upended crates.

Fig. 6 is a horizontal section, substantially on the line 6—6 of Fig. 5.

Fig. 7 is a vertical section, substantially on the line 7—7 of Fig. 6.

In the drawing, wherein for the purpose of illustration is shown a preferred embodiment of the invention, and wherein similar reference characters designate corresponding parts throughout the several views, the letter A designates a support, B designates the new display container forming a rim and trim, and C designates means to secure the container B to the support A.

The support A is shown as made up of a plurality of crates, such as four conventional slatted

25 crates (for example, orange crates) each having side walls 10, end walls 11, a bottom wall 12 and open mouth 13. Preferably they are upended and grouped together with their mouths 13 inwardly and their bottom walls 12 and some 30 of their side walls 10 outwardly, as in Fig. 6, and a suitable covering 14 for the outer faces of these side walls 10 and bottom walls 12 may be provided, such as a display sheet, plain paper, crepe paper, cloth and the like, or combinations of 35 these. The upper end portion 15 of the covering may be secured to the walls 10 and 12 as by means of staples 16, which are subsequently covered by the display container B.

This assembly of four orange crates is given by

40 way of example, since the display container B may be provided for an assembly of two, six, eight or nine crates, and apple crates (which are generally not quite as long as orange crates) may be substituted for the latter. It is important that 45 the support A present substantially vertical walls and a substantially horizontal upper wall which latter forms part of the support and contact surface for a portion of the articles displayed, since the novel display container A provides a rim or border but provides no appreciable upper wall.

As shown more particularly in Figs. 2, 3 and 4, the collapsed display container B provides a flat package, taking up but little space. It has an upwardly-extending border wall or rim portion 20, downwardly-extending flange portion 21 55 which is, preferably, a downward continuation of the wall portion 20, an inner wall or inner rim portion 22 and a second flange portion 23 constructed and arranged, when the display container B is in use, to extend substantially hori-

zontally from the lower end of the wall portion 22. That is, in use, the flange portion 23 forms substantially a right angle with the portions 20, 21 or 22. All these portions are preferably parts of a sheet of suitable material as corrugated board, scored or otherwise weakened to provide the longitudinally-extending folds 24 and 25. The folds 24 are at the juncture of the wall portions 20 and 22 and the folds 25 are at the juncture of the wall portion 22 and flange portion 23. 10 In the event the container B is employed to rim or border the upper ends of four crates, assembled as described, the sheet is suitably transversely slit, as at 26 to provide, with the brought-together ends of the sheet, four sections of the inner wall portion 22 and flange portion 23. From the bases of these slits 26, the wall portion 20 and flange portion 21 are transversely scored, as at 27, so as to provide, with the brought-together ends of the sheet, four sections of the 20 wall portion 20 and four sections of the flange portion 21. At these ends, the two adjacent sections of portions 20 and 21 may be joined by a flexible means 28 as a strip of adhesive tape. Thus, the display container B may be folded flat, 25 as in Figures 2, 3 and 4.

However, in use, in connection with a support A, such as four upended crates as described, the container B is arranged with the four sections of the flange portion 23 substantially horizontal (as in Figure 1) and the four sections of the flange portion 21 telescoped over the upper end of the support A until the sections of the flange portion 23 contact the edge portion of the upper face of the support A (that is, the outer edge portions of the four end faces of the crates) and extend thereover, as in Figures 5 and 7.

Thereupon the means C, which may be staples, may be employed to secure the sections of the flange portion 23 to the support A.

Thus there is provided a rim or wall, upstanding from the support A and adapted to retain articles piled or placed upon the upper face of the support A and upon, of course, the sections of the flange 23.

This provides not only the rim or wall just mentioned but the flange 21, which hugs the outer faces of the upper end portions of the vertical walls of the support A, prevents bulging of the wall 20, aids in preventing accidental movements of the crates, one with respect to the others, and hides the staples 16. The outer face of either the rim portion 26 or flange portion 21 (or both) may be provided with suitable indicia.

The spectator, when the support A and display container B retain piled up articles, such as fruit, gets the impression that he is looking into the open mouth of a container of the articles, with the display container B being a decorative border. Thus, it is not intended to provide for a display stand, a rim assembly jutting out beyond the vertical walls of a support since, when such jutting rim assembly is filled with articles, as fruit, the entire device is apt to topple.

As may be appreciated from Figure 7, the wall portion 20 is not apt to spread outwardly, due to the bracing effects of the flange portion 21.

Because of the bracing effects of the flange portion 21 on the wall portion 20, the flange portion 23 may be quite narrow, thus economizing in material.

By employing the slatted, upended orange crates to form the support A, arranged as described and not providing a continuous bottom wall to the display container B, there are formed a plurality of air-circulating openings 30 in the upper face of the support A, as may be seen in Fig. 5, so that there will be a desirable circulation of air around the articles displayed, since the flange 23 does not cover the majority of these openings 30.

Various changes may be made to the form of the invention herein shown and described without departing from the spirit of the invention or scope of the claims.

What is claimed is:

1. In a display stand, a support having upwardly-extending walls and an upper horizontal wall, a covering material secured over the exposed exterior walls of said support, a display container mounted on said support including a strip of material comprising a flange surrounding the upper end of the support and covering the upper portion of said covering material and an integral upwardly extending rim for supporting and confining produce to be displayed above the support, and horizontal flanges extending from the juncture of said flange and rim portions for securing to the upper edges of the upper horizontal wall of the support.

30 2. In a display stand, a support comprising a plurality of crates each having a plurality of upright spaced slatted walls with end walls providing a base for the stand and an upper horizontal wall, said slats providing upwardly extending apertures through the upper horizontal wall through which air may circulate, and a display container comprising a flange surrounding the crates and extending upwardly therefrom to provide a rim for supporting and confining produce to be displayed above the horizontal apertured wall of the stand, and means extending horizontally from said flange and rim inwardly over the peripheral edges of said horizontal stand wall for attachment thereto.

40 3. In a display stand, a support comprising a plurality of crates, each crate having upwardly extending spaced apart slats and a top wall, said crates when placed in juxtaposition providing a plurality of openings between said slats, and a display container mounted on said support, said display container comprising a vertical flange adapted to enclose the upper ends of said crates, a flange extending downwardly from the upper edge of said vertical flange and a horizontal flange extending inwardly from the lower edge of said last named flange, said horizontal flange resting upon the top wall of said support, said openings in the top wall serving to ventilate produce held within the display container.

60 HAMLET LEE MOREMEN.
